UNITED STATES PATENT OFFICE.

JOHN F. BRADY, OF COLORADO SPRINGS, COLORADO.

FLYING MACHINE.

Application filed April 24, 1920. Serial No. 376,250.

To all whom it may concern:

Be it known that I, JOHN F. BRADY, a citizen of the United States, and a resident of Colorado Springs, in the county of El Paso and State of Colorado, have invented certain new and useful Improvements in Flying Machines; and I do hereby declare that the following is a full, clear, and exact description thereof, reference being had to the accompanying drawings, and to the letters of reference marked thereon, which form a part of this specification.

This invention relates to improvements in flying machines, and consists of the matters hereinafter described and more particularly pointed out in the appended claims.

The object of the invention is to provide a simple and efficient means, applicable to any type of flying machine, by which the buoyancy thereof may be readily increased and maintained, after the same has reached a predetermined altitude in its flight. The invention is herein illustrated and described as applied to and used in connection with a heavier-than-air type of a flying machine, but may as readily be applied to and used in connection with a lighter-than-air type of flying machine.

The advantages of the invention will be pointed out as I proceed with my specification.

In the drawings:

Figure 1 illustrates, in side elevation, a modern type of aeroplane to which my invention has been applied.

Referring now in detail to that embodiment of the invention illustrated in the accompanying drawings:—5 indicates the fuselage of the aeroplane, 6 indicates the supporting planes, and 7 indicates the propeller at the front or bow end 8 of the fuselage. Said propeller is driven in the usual manner by an engine or motor 9, located in the bow end of the aeroplane. 10 indicates the aviator's cockpit and 11 the observer's cockpit. 12 indicates the landing gear, and 13 the skid associated with the landing gear which skid is of the usual kind arranged near the vertical and horizontal rudders 14.

15 indicates a longitudinal header pipe, closed at both ends and preferably secured by means of brackets 16 to the top surface of the fuselage 5, along its longitudinal median line, back of the observer's cockpit 11. Throughout the length of said pipe are

disposed, longitudinally-spaced valve casings 17, from which rise perpendicular branch pipes 18. Each of said pipes terminates in a bracket plate 19, by means of which is provided a plurality of stepped platforms or bases 20, one for each pipe 18, said platforms being defined fore and aft by upright, longitudinally spaced flanges 21.

Secured in suitable manner to each stepped platform, is the open bottom end of a vertically, elongated balloonette, or bag 22, made of a soft, flexible, air-tight textile material. Each bag in cross-sectional area approximates the horizontal axes of its associated platform 20. Each bag is collapsible in accordion pleated folds upon its associated platform as shown in the drawings, the fore and aft vertical flanges 21 of the platform 20, providing a support for the balloonette or bag, when in this position.

Each valve casing 17, has associated with it an arm 23 for actuating the contained valve mechanism. The several arms are connected by links 24 to associated actuating levers 25, pivoted on the side of the fuselage adjacent to the cock-pit 10, within convenient reach of the aviator.

Connected to the pipe 15, between two of the valve casings 17, is a short pipe 26, which forms a continuation of a long pipe 27, extending along the side of the fuselage 5. The forward end of this pipe enters into the bow 8 where it is connected to an air pump 28 within said bow.

The pump 28 (shown in dotted lines) has an air inlet 29, and is adapted to be driven by the engine 9 in any convenient manner,—suitable means (not shown) being provided to connect or disconnect the pump to and from the engine 9. In the pipe 27, adjacent the levers 25 and within convenient reach of the aviator is a hand valve 30, which may be actuated to control the escape of air from the pipe 27 when it is desired to deflate the balloonettes 22.

The operation and use of my invention as applied to the aeroplane described is as follows:—Assume that the aeroplane is in flight and that the balloonettes are deflated and are collapsed upon their associated platforms. When the proper high altitude (say 30,000 feet) is reached, where the rarefied air approximates about four pounds per square inch of surface, one or more of the levers 25 may be actuated to open one or more of the valves 17, in the pipe 15 for the associated

balloonette 22. The pump 28 is then connected with the engine 9 and the rarefied air is drawn or sucked in through the inlet 29 and is discharged through the pipes 27 and 5 26 into the header pipe 15, and thence through the open valve or valves 17, into the associated balloonettes,—thus expanding and filling them with said rare air. When 10 the desired number of balloonettes have thus been inflated with the rarefied buoyant air, the levers 25 are operated to close the valves 17, and the pump 28 is disconnected from the engine 9.

The advantage of using air of high altitude to fill the balloons is apparent. The 15 air of the higher altitude will manifestly give buoyancy to the aeroplane in the denser atmosphere of the lower altitude, the containers or balloons inflated with the air of 20 the high altitude floating on the denser air nearer the earth, as a cork or any lighter than water body will float on the water. The buoyancy is inversely in proportion to the pressure of the air at the higher altitude, as compared to the pressure of the 25 denser air at the lower altitude. This proportion is readily calculable.

In addition, the air of the higher altitude has its different elements reduced in proportion 30 and when brought to earth, besides being used as a lifting agent, it may be used for many purposes, owing to the natural reduction of the several elements.

Any number of balloonettes or containers 35 may be used, and they may be applied to flying machines of any construction or design,—that shown in the drawings being merely for purposes of illustration.

While in describing my invention, I have 40 referred to many details of construction and arrangement, it will be understood that the invention is in no way intended to be limited thereto, except in so far as may be pointed out in the appended claims.

45 I claim as my invention:—

1. In combination with a flying machine including a fuselage having a cockpit and an engine in said fuselage forward of said

cockpit, a header pipe secured to the median line of said fuselage back of the cockpit, upright branch pipes, valve devices connecting said upright branch pipes with said header pipe, an air pump in the fuselage adjacent the engine and adapted to be driven thereby, a conduit connecting the pump with the 55 header pipe, a plurality of collapsible air tight bags, one connected to each upright branch pipe, and means carried by the fuselage adjacent the cockpit for actuating said valve devices.

2. In combination with a flying machine including a fuselage having a cockpit and an engine in said fuselage forward of said cockpit, a header pipe secured to the median line of said fuselage back of the cockpit, upright branch pipes, valve devices connecting said upright branch pipes with said header pipe, an air pump in the fuselage adjacent the engine and adapted to be driven thereby, a conduit connecting the pump with the 60 header pipe, a plurality of collapsible air tight bags, one connected to each upright branch pipe, and means carried by the fuselage adjacent the cockpit for actuating said valve devices.

3. In combination with a flying machine including a fuselage having a cockpit, a header pipe mounted on the fuselage to the 65 rear of the cockpit and extending in the longitudinal median plane of said fuselage, a plurality of platforms mounted on the header pipe, air tight bags one on each platform, and a conduit leading to said header pipe, from a suitable source of air supply.

In testimony that I claim the foregoing as my invention, I affix my signature in the presence of two witnesses, this 19th day of April, A. D., 1920.

JOHN F. BRADY.
